UNITED STATES PATENT OFFICE.

THOMAS J. MACMURTRY, JR., OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WELT-INDENTING MACHINE.

1,290,619.

Specification of Letters Patent.

Patented Jan. 7, 1919.

Application filed October 26, 1917. Serial No. 198,613.

To all whom it may concern:

Be it known that I, THOMAS J. MACMURTRY, Jr., a citizen of the United States, residing at Beverly, in the county of Essex and State of Massachusetts, have invented certain new and useful Improvements in Welt-Indenting Machines; and I do hereby declare the following to be a full, clear, and exact description of the invention, such as will enable others skilled in the art to which it appertains to make and use the same.

This invention relates to welt indenting machines and more particularly to that type of welt indenting machines which employs a rotary tool, known commercially as "wheeling machines."

In machines of this type the tool, by which the impressions or indentations are made in the marginal portion of the sole, is usually heated to render the indentations firm and lasting. It has been customary heretofore to employ a metal guard or shield, which extends between the end of the tool and the upper of the shoe which is being operated upon, in order to prevent the upper from being injured by the tool during its operation. It has been found that if metal is employed for the material of these guards, the heat of the tool is transmitted to the guard and the upper is discolored by rubbing against the heated guard. To overcome this difficulty it has been proposed to use a guard of some material other than metal which will not transmit heat from the tool. To this end guards have been made of rawhide and of canvas, but as they wear out rather quickly their renewal has caused inconvenience and loss of time.

The object of the present invention is to provide a guard or shield having the desired qualities which can be renewed with a minimum loss of time. An ancillary object is to provide a mounting, permitting removal of the guard from the tool when desired, and permitting required adjustments.

The features of the invention through which these objects are accomplished will be explained in the following description which is elucidated by the accompanying

drawings illustrating the preferred form of the invention, in which:

Figure 1 is a side elevation of a portion 55 of a welt indenting machine of the type illustrated and described in Letters Patent of the United States No. 1,173,364, dated February 29, 1916, granted to United Shoe Machinery Company as assignee of Harry 60 C. McClure and John J. Heys, having the present improved guard or shield applied to the tool thereof; and Fig. 2 is a plan of the parts shown in Fig. 1 looking in the direction of the arrow A.

In the embodiment of the invention illustrated in the drawings the frame 2, work supporting table 4, rotated by the gear 6 carried on the sleeve 8 journaled on the frame, the table tipping frame 10, the rotating indenting tool 12 journaled in its vibrating tool carrier 14, having a bearing on the shaft 8, and the driving shaft 16, rotated by the belt 18 on the pulley 20; all may be of the same construction and design 75 as like parts in the patent to McClure and Heys hereinbefore referred to. The present invention distinguishes from the machine of said patent by being provided with a boss 22 rising from the frame 2 in 80 the rear of the tool carrier 14 to which is secured a tool guard frame 24. The frame 24 comprises two side plates (best shown in Fig. 2) which bend to the right so as to extend symmetrically at each side of 85 the tool 12 which is off center relative to the table, as in said patent, and these plates are connected by a rear tie plate 26 which bears against and is adjustably bolted to the boss 22 by the bolt 28. The side plates 90 are of general triangular shape and at the upper angles they are further tied together by a hub 30 (Fig. 2). Within the hub 30 is secured a pivot pin 32 which projects from each end thereof and on these projecting ends there is hung a tool guard carrier 34.

The tool guard carrier 34 comprises two side arms which are curved inwardly, at their ends 36, toward the tool 12 and also beveled on their outer faces 38 (Fig. 1) so that these faces lie substantially on the plane of the end of the tool which abuts the upper of the shoe being operated upon

(indicated by dot and dash lines, Fig. 1). From each side arm of the tool carrier there projects a lug 40 and on each lug there is secured a pivoted dog 42 each having its face adjacent the carrier eccentric to its pivot and preferably provided with teeth 44. Lying between the dogs and side arms and running over the curved ends 36 and across the tool 12 is a strip of material 46, preferably canvas or rawhide, which comprises the guard or shield for protecting the shoe upper.

The working position of the tool guard carrier is determined with accuracy by the adjustment of a screw 48 (Fig. 1) carried on one of the side plates of the tool guard frame 24, against which a lug 50 on the carrier abuts. The tool guard carrier is locked against upward movement, when in working position, by a second lug 52 (Fig. 2) on the carrier, at the rear of the pivot pin 32, bearing on a latch 54, pivoted on a pin 56 (dotted lines Fig. 1) carried on one of the side plates of the tool guard frame 24. The latch 54 is spring pressed toward the carrier by a suitably connected spring 58 thereby being continually maintained in position to engage beneath the lug 52 whenever the tool guard carrier is in working position. The carrier is removed from working position by withdrawing the latch from beneath its lug and then turning the carrier upward about its fulcrum on the ends of the pivot pin 32, which pin, it will be noted, is located sufficiently above the tool 12 to provide for the guard clearing the tool as the carrier describes its arc of movement.

In order to permit adjustment of the tool guard carrier, to accommodate it to different sizes of indenting tools, the sleeve 30 is bored eccentrically and one projecting end of the pivot pin 32 is provided with a screw head, as at 60 (Fig. 1). By loosening the set screw 62, which secures the pivot pin in place, and rotating the pivot pin the side arms of the carrier may be moved to bring their curved ends 36 into proper relation to the end of the tool being used. Preferably the guard, when lying against the ends 36, is in contact with the end of the tool. As a result of such an adjustment the position of the stop lug 52 will be changed. Consequently the latch pin 56 is also provided with an eccentric, as shown by dotted lines in Fig. 1, having a screw head 64, which may be turned to raise or lower the latch as may be necessary to maintain its proper relation to the stop lug.

In practice, if canvas tape is used as the guard material, a piece of indefinite length will be held in place by the dogs 42 as indicated by the tape roll 66 in Fig. 2. As any portion over the tool 12 wears out, the dogs

are loosened, a fresh portion of the tape is drawn laterally across the tool and, after turning down the dogs to hold the tape taut, work may immediately be resumed. The renewal of a worn section is made in like manner for any other flexible guard material which may be used.

Having thus described the preferred form of the invention and its mode of operation, the scope of the invention will be found defined in the following claims.

What is claimed as new, is:

1. In a machine for operating on the marginal portions of the sole of lasted shoes, a tool; a guard between the tool and the upper; and means for holding the guard in position, constructed and arranged to permit the guard to be moved laterally across the tool to bring the wear upon different portions of the guard.

2. In a machine for operating on the marginal portions of the sole of lasted shoes, a tool for operating on said portion of the shoe, a guard, comprising an elongated strip, between the tool and the upper; and means for holding the strip in position while permitting it to be shifted, relative to the tool, in the direction of its length.

3. In a machine for operating on the marginal portions of the sole of lasted shoes, a tool for operating on said portion of the shoe, an elongated flexible guard for the tool; a guard holder; and means for sustaining the guard on its holder permitting different portions of the guard to be brought between the tool and the upper.

4. In a welt indenting machine, a rotary tool; a guard comprising a strip of material considerably longer than the diameter of the tool; a guard holder having a guard supporting portion at opposite sides of the tool; and clamps for securing the guard to said supporting portions, whereby, when the clamps are loosened the guard may be drawn past the tool to renew a portion which is worn out.

5. In a welt indenting machine, an indenting tool, a flexible guard for said tool, a guard holder having a pair of arms one at either side of the tool; means for securing the flexible guard to the ends of said arms and taut across the end of the tool therebetween; and means for adjusting the guard holder toward and from the end of the tool which is adjacent the upper of the shoe being operated upon.

6. In a welt indenting machine, an indenting tool; a flexible guard for said tool; a guard holder pivoted to swing upward to carry the guard away from the tool; means to determine the operative position of the guard when the holder is swung down; and means for latching the guard holder in such position.

7. In a machine for operating on the marginal portions of the soles of lasted shoes, a

tool; a guard holder comprising arms, having rounded ends, located at opposite sides of said tool; a flexible guard, secured to said holder, lying in contact with said rounded ends and bridging the space therebetween; and means for adjusting said guard holder to bring the guard into contact with the tool.

8. In a machine for operating on the marginal portions of the soles of lasted shoes, a

tool; a guard holder, carrying a guard between the tool and the upper, mounted for adjustment relative to the tool; a latch to engage a catch on the guard holder and maintain it in operative position; and means for adjusting the latch to compensate for variations in the position of the catch due to adjustments of the guard holder.
